UNITED STATES PATENT OFFICE.

CHARLES R. KEISER, OF DAYTON, AND THEODORE R. RIKE, OF WEST ALEXANDRIA,
OHIO.

FOLDING HAND BAG.

Application filed July 9, 1927. Serial No. 204,556.

The invention relates to improvements in folding hand bags.

The object of the present invention is to improve the construction of folding hand bags and to provide a simple, practical and inexpensive hand bag of strong and durable construction adapted to be readily unfolded and extended to form a luggage carrier and capable of being readily folded and compactly arranged in an attractive form simulating a pocket book for convenient carrying when empty.

A further object of the invention is to provide a folding hand bag of this character adapted to eliminate all seams at the points of greatest strain and so constructed as to enable the back to take a natural fold at the desired points in folding the bag to its compact or folded condition.

Another object of the invention is to equip the folding hand bag with stiffened flaps between which the body of the bag is folded and to provide supporting straps connecting the flaps for holding the body of the bag in its folded position and for also cooperating with the stiffened flaps to maintain the body of the bag in rectangular form when the body of the bag is unfolded for use as a luggage carrier.

A further object of the invention is to enable the supporting straps which are connected with the stiffened flaps to pivot or swing from one position to the other and thereby obviate the necessity of fastening and unfastening straps in folding and unfolding the hand bag.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a perspective view of a hand bag constructed in accordance with this invention and shown folded.

Fig. 2 is a similar view of a hand bag

being shown unfolded and arranged for use as a luggage carrier.

Fig. 3 is a detail vertical sectional view through one side of the hand bag, the parts being arranged as shown in Fig. 2.

Fig. 4 is a plan view of the sheet or blank which forms the body of the hand bag.

Fig. 5 is a detail horizontal sectional view through one end of the folding hand bag, the parts being arranged as shown in Fig. 2.

Fig. 6 is a detailed view of one of the lower corners of the body of the bag, the latter being collapsed and the triangular flap being shown in dotted lines.

In the accompanying drawing in which is illustrated the preferred embodiment of the invention, the folding hand bag comprises in its construction a collapsible and foldable body constructed of a single sheet of any suitable flexible material. The single sheet or body blank which is illustrated in plan view in Fig. 4 of the drawing is recessed or cut away at opposite sides of the center to provide triangular flaps 1 and to form end sections 2 and 3, the bottom section or portion 4 and the side portions or sections 5 lying between the flaps 1 and the end sections 2 and 3. The end sections which form the end walls of the hand bag are overlapped and secured together by a suitable adhesive such as cement or any other suitable means as will be readily understood. The end section 2 of each end wall extends to the center line of the end wall and is narrower than the section 3 which overlaps the end section 2 beyond the center line forming a thickened reinforced portion at one side of the center line of the end wall thereby providing a natural line of fold at the center indicated by the dotted line 6. The triangular end flap overlaps the bottom end portions of the sections 1 and 2 and is secured to the same by an adhesive or any other suitable means and the triangular end flap is adapted to fold inwardly along the dotted line 6 of Fig. 2 of the drawing to permit the body portion of the bag to collapse preparatory to folding the body into the position illustrated in Fig. 1 of the drawings. In Fig. 4 of the drawing the bottom section is defined by the transverse dotted lines 7 and the longitudinal dotted lines 8 which indicate the bending of the

flaps at the corners of the bag to form the end walls and also the end extremities of the bottom section of the body. In the collapsing of the body of the bag to arrange 5 the sides thereof flat against each other preparatory to folding the body into compact form, the bottom of the bag folds on the dotted lines 9 and 10 of Fig. 4 of the drawing. The bottom section in collapsing moves 10 downwardly and the end portions of the bottom section collapse inwardly on the dotted lines 10 and fold with the end walls of the body in the inward collapsing thereof. After the body is collapsed and the sides 15 brought flat against each other with the end walls folded between the sides, the lower portion of the body of the bag is folded upon the intermediate portion and the intermediate and bottom portions are then 20 folded against the top portion of the body, making two folds to arrange the body in compact form as illustrated in Fig. 1 of the drawing.

The body of the bag is provided at opposite sides at the upper portions thereof with 25 reinforced side flaps 11 consisting of sheets of the same material as the body of the bag provided at their inner faces with a layer 12 of suitable stiffening material. The 30 stiffening material which may be of any desired character may, of course, be omitted if desired, but it is preferable to employ the stiffening means and the side flaps are secured to the body of the bag at the upper 35 edges thereof by top extensions 13 which are folded inwardly and suitably secured to the inner face of the body of the bag at the upper edges thereof. This also provides a finish for the upper portion of the interior of the body of the bag in addition to 40 attaching the side flaps thereto. The side flaps which extend entirely across the body of the bag to the end walls thereof practically conceal the folded body of the bag 45 which is supported in its folded position by a pair of straps 14 of suitable flexible material preferably of the same material as the body of the bag and secured at their ends to the exterior of the end flaps by suitable 50 fastening devices 15 which form pivots for the straps 14 to permit the same to be readily swung from the position illustrated in Fig. 1 of the drawing to that shown in Fig. 2 and from the position shown in Fig. 2 to that illustrated in Fig. 1. The fastening devices 55 15 may consist of snap fasteners and will enable the straps to be detached if desired. When the straps are arranged as shown at Fig. 1, they hold the side flaps 11 together 60 and prevent separation of the same and support the folded body of the bag between the side flaps. The hand bag when in this position is compact and presents a neat and attractive appearance and may be conveniently carried. When the hand bag is ex- 65

tended and unfolded the straps extend across the end walls of the body of the bag and connect the side flaps and cooperate with the same in maintaining the body of the bag in its natural rectangular shape illustrated 70 in Fig. 2 of the drawing. This enables the hand bag to present a neat and attractive appearance when in use as a luggage carrier.

The hand bag is provided at the upper edges at opposite sides with suitable handles 75 16 which may be of any desired construction. The handles may consist of strips of material composing the body of the bag and they may be secured by suitable adhesive to the inner faces of the sides of the body by 80 an adhesive. In addition to an adhesive as a fastening means the hand bag may be stitched as indicated by the dotted lines in Figs. 1 and 2 of the drawings or any other suitable means may be employed in securing 85 the sections or other portions of the hand bag together and the body portion is designed to be provided at opposite sides at its edges with snap fasteners 17 or other suitable means for holding the mouth or upper 90 edges of the body closed when the hand bag is folded. The hand bag may be made exceedingly cheap or expensive materials may be employed in its construction if desired.

By constructing the body of the hand bag 95 in one piece, with the exception of the stiffened flaps, all seams at the points of greatest strain are eliminated and the triangular flaps at the bottom of the body at the lower 100 ends of the end walls and the adjacent end portions of the bottom section collapse inwardly with the end walls and the hand bag takes a natural fold along the side seams formed by the sections of the end walls. Both of the end flaps are shown free from 105 the body except at the point of attachment at the upper edges of the body, but it is only necessary that one of the side flaps be free in order to accommodate the folded body between the end flaps. The small connecting 110 straps which prevent the bag from spreading at the bottom when folded also support the bag and prevent it from dropping out of place and when the body of the bag is unfolded and arranged for use as a luggage 115 carrier, the said straps extend across the end walls and connect the reinforced side flaps and prevent the bag from spreading beyond its natural width thereby maintaining the 120 rectangular formation of the bag and the desired effect for good appearance. The stiffened side flaps assist in maintaining the bag square and in definite shape when used as a luggage carrier.

What is claimed is:

1. A folding bag including a body having side and end walls and a bottom, and collapsible inwardly to arrange the side walls flat against each other, side flaps secured to the body at the upper edges thereof, said 130

- body being foldable into compact form between the side flaps, and straps connecting the side flaps at the bottom and extending beneath and supporting the body in its 5 folded position, said strips being movable from said supporting position to permit unfolding of the body and extending across the end walls and connecting the side flaps when the body is unfolded.
- 10 2. A folding bag including a body having side and end walls and a bottom, and collapsible inwardly to arrange the side walls flat against each other, side flaps secured to the body at the upper edges thereof, said body 15 being foldable into compact form between the side flaps, and straps connecting the side flaps at the bottom and supporting the body in its folded position, said straps being pivoted to the side flaps and arranged to swing 20 into and out of their supporting position and extending across the end walls and connecting the side flaps when the body is unfolded.
3. A folding bag including a body having 25 side and end walls and a bottom, and collapsible inwardly to arrange the side walls flat
- against each other, and stiff side flaps secured to the body at the upper edges thereof and extending entirely across the body and maintaining a straight line along the top of the 30 body at each side thereof at all times, said body being foldable into compact form between the side flaps.
4. A folding bag including a body having side and end walls and a bottom, and collapsible inwardly to arrange the side walls flat against each other, stiff side flaps secured to the body at the upper edges thereof and extending entirely across the body and maintaining a straight line along the top of the 35 body at each side thereof at all times, said body being foldable into compact form between the side flaps, and straps extending across the ends of the body and connecting the ends of the stiff side flaps at the lower 40 portions thereof and movable to a position beneath the bag body when the same is folded.

In testimony whereof we hereunto affix our hands.

CHARLES R. KEISER.
THEODORE R. RIKE.
